[57] CLAIM

The ornamental design for a conveyor trough housing
or similar article, as shown and described.

DESCRIPTION

FIG. 1 is a perspective view of the conveyor trough
housing or similar article showing my new design;
FIG. 2 is an end elevational view thereof;
FIG. 3 is a side elevational view thereof; and
FIG. 4 is a perspective view thereof showing the side
and end opposite to that shown in FIG. 1.

FIG. 4
